The ornamental design for an adapter for fixing a magnetic sensor, as shown and described.

DESCRIPTION

FIG. 1 is a top perspective view of an adapter for fixing a magnetic sensor, showing my new design;
FIG. 2 is a bottom perspective view thereof;
FIG. 3 is a front elevational view thereof;
FIG. 4 is a left side elevational view thereof;
FIG. 5 is a right side elevational view thereof;
FIG. 6 is a top plan view thereof;
FIG. 7 is a rear elevational view thereof;
FIG. 8 is a bottom plan view thereof;
FIG. 9 is a perspective view thereof with a lock opened;
FIG. 10 is a front elevational view thereof with a lock opened;
FIG. 11 is a left side elevational view thereof with a lock opened;
FIG. 12 is a top plan view thereof with a lock opened;
FIG. 13 is an enlarged cross-sectional view thereof, taken along the line 13-13 in FIG. 6;
FIG. 14 is an enlarged cross-sectional view thereof, taken along the line 14-14 in FIG. 3; and,
FIG. 15 is an enlarged cross-sectional view thereof, taken along the line 15-15 in FIG. 3.
The broken line showing in FIGS. 13, 14, and 15 of the interior surfaces of the adapter for fixing a magnetic sensor illustrate portions of the adapter for fixing a magnetic sensor which form no part of the claimed design.
